UNITED STATES PATENT OFFICE

ALBERT H. FISHER, OF EAST CLEVELAND, OHIO

WINDOW CONSTRUCTION

Application filed May 5, 1927. Serial No. 189,007.

This invention as indicated relates to a window construction. More particularly it comprises a construction especially adapted for use with wooden windows which will at all times maintain the same in sliding engagement with the window frame irrespective of expansion or shrinkage of the sash or associated parts. It also includes a pair of guide members preferably formed of metal adapted to be associated respectively with the side of the window frame and the window sash and permitting adjustment or compensation between said parts so that they will not bind in the event of expansion of the wooden window frame or sash, and also to prevent shrinkage of the wooden parts to cause such loose engagement that noisy vibration and leakage of air at the edges of the window will result.

It has heretofore been proposed to suspend windows resiliently so that motion of the sash in one direction would push against the guide member at one lateral edge and at the opposite edge would exert tension upon the adjacent guide member. The present invention contemplates a similar arrangement, but also has in view establishing between one of the guide members and the supporting structure, an adjustment which will permit said guide to assume any necessary angle to prevent binding of the window, or any interference with sliding adjustment thereof.

To the accomplishment of the foregoing and related ends, said invention, then consists of the means hereinafter fully described and particularly pointed out in the claims.

The annexed drawing and the following description set forth in detail certain structure embodying the invention, such disclosed means constituting, however, but several of various structural forms in which the principle of the invention may be used.

In said annexed drawing:

Fig. 1 is a side elevation showing a window construction embodying the principles of my invention; Fig. 2 is a sectional view taken along the line 2-2 shown in Fig. 1; Fig. 3 is a similar view taken along the line 3-3 shown in Fig. 1; Fig. 4 is a fragmentary perspective view of the outer guide tube shown

in Fig. 1; Fig. 5 is a fragmentary view showing one construction of guide tube and resilient supporting member; Fig. 6 is a view similar to Fig. 5 showing a modified form of supporting member; Fig. 7 is a top plan view of a lateral edge of a window sash fitted with a modified form of outer guide tube; and Fig. 8 is a transverse sectional view of a modified form of inner guide member.

As is clearly shown in Fig. 1, a wooden window sash 1 is provided in its lateral edge 2 with a channel 3 extending the entire length thereof. Within said channel is inserted a slotted tubular member 4 of substantially the entire length of the window sash, said member having resilient tongues 5 formed by slitting the rearward portion of said member opposite its open or slotted side and adjacent each of its ends and bending resilient strips or tongues rearwardly therefrom. The ends of said strips are secured by any suitable means such as screws 6 extending through apertures 7 adjacent said ends and into the base of the channel or groove formed in the lateral edge of the window sash.

The tubular member 4 is substantially cylindrical in form with a longitudinal slot 8 extending throughout its length on its outer side and is of a size to slidably engage a guide member having a bead or tubular edge 11 formed on plate or base 12 adapted to be secured to the adjacent side of the window frame 13 by means of screws 14 or other fastening means. Thus there is provided a cylindrical guide member 11 within a cylindrical sleeve 4, one of said members being firmly secured to the window frame and the other member being held in self-adjusting relation thereto within the groove at the lateral edge of the window sash. This construction, it will be noted, provides for free adjustment of the slotted cylinder 4 upon the cylindrical guide member 11. The window sash may expand or contract or be moved laterally or swung about a vertical axis without causing binding action on the guide members inasmuch as the guide member 4 is flexibly supported. The degree of adjustment, between the window sash and window frame, it will be noted, is relatively slight but the range of

movement of the guide member 4 is fully adequate to take care of the expansion and contraction which causes much difficulty in connection with the raising and lowering of windows at certain seasons of the year. 5 This, as stated, is particularly true of windows of wooden construction, such as are used in dwellings, which often swell to such an extent that it is impossible to move them or which become so loose that they will rattle and cause much annoyance.

While the strips or tongues 4 are adequate to position the outer tubular member, additional or substitute means may also be employed. Thus there is shown in Fig. 1, slotted plates 15, 16 attached to the ends of the outer tube and bearing against the ends of the lateral member of the sash. The slotted plate is soldered, welded, or secured in any 15 other suitable manner to the top edge of the outer tube and because of the wide slot 17 and the thin gauge of the material of the plate, the elasticity of the slotted tubular member is not materially affected insofar as 20 relates to its engagement with the inner tubular member. Said slotted plates form air stops to prevent air currents in the guide channels.

The outer tube may be formed with integral tongues as shown in Fig. 5 or may have 30 separate strips 21 spot welded thereto, as is shown in Fig. 6, or secured in any other suitable manner to the tubular member 22 adjacent the respective ends.

35 As is shown in Fig. 7, the outer tube 23 may be formed of a strip of sheet metal folded reversely at either side upon itself to provide an inner cylindrical portion and overlying side portions 24. A pair of plates 25, 26 may be secured to the respective side portions at each end of the tubular member 40 to maintain it in engagement with the lateral grooved portion 27 of the sash.

A modified form of inner tubular member 45 may also be employed, that shown in Fig. 8 being formed of a single strip of metal having a flat base 31 with side portions 32 bent toward each other and having marginal portions 33 of arcuate cross-section. The securing screw 34 or other fastening element is 50 provided with a beveled head 35 adapted to contact with the inclined inner faces of the side portions and thus serve as an adjusting element for spreading apart or relieving 55 the spreading action upon the arcuate marginal portions. In this manner the inner guide member may be given any desired degree of frictional engagement with the outer guide member.

60 In addition to thus compensating for expansion and contraction, the apparatus may be adjusted to provide a degree of frictional engagement between the guide members which may be adequate to maintain the window in adjusted position without the use of

the usual cords, pulleys and weights. Should the window be of somewhat more than usual weight or size, it may be found desirable to combine with the frictional suspension a set of cords, pulleys and weights. This may be more readily accomplished by placing the inner cylindrical guide member upon the window sash and placing the outer flexibly held slotted cylindrical member within a channelway in a window frame. The cords in such event would be concealed within the tubular guide and a very much improved appearance would be given to the window over the type of construction now in general use. 70

Other modes of applying the principle of my invention may be employed instead of the one explained, change being made as regards the structure herein disclosed, provided the means stated by any of the following claims or the equivalent of such stated means be employed. 80

I therefore particularly point out and distinctly claim as my invention:

1. A window construction having in combination a pair of guide members adapted to be slidably engaged for relative longitudinal sliding motion and interlocking against lateral disengagement, one of said guide members being adapted to be mounted on the frame of the window and the other of said guide members being adapted to be mounted on the sash of the window, and means for movably associating one of said guide members with its support so that it may seek free adjustment in relation to its companion guide member and at the same time substantially prevent the passage of air through said connection. 95

2. A window construction having in combination a pair of substantially cylindrical guide members adapted to be telescopically engaged for relative longitudinal sliding motion, and interlocked against lateral disengagement, one of said guide members being adapted to be mounted on the frame of the window and the other of said guide members being adapted to be mounted on the sash of the window, and means for movably associating one of said guide members with its support so that it may seek free adjustment in relation to its companion guide member and at the same time substantially prevent the passage of air through said connection. 100

3. A window construction having in combination a pair of guide members adapted to be slidably engaged for relative longitudinal sliding motion, and interlocked against lateral disengagement, one of said guide members being adapted to be attached to the frame of the window and the other of said guide members being adapted to be movably associated with the sash of the window and a member associated with one of said guide members for supporting the same for free adjustment with respect to its companion 110

guide member and substantially preventing the passage of air through said connection.

4. A window construction having in combination a window sash provided with a groove in each lateral edge, a pair of cylindrical guide members adapted to be telescopically engaged, one of said guide members comprising an elongated cylindrical member slotted at one side and having a pair of rearwardly projecting resilient tongues connected adjacent its ends respectively, said guide member being received within one of the grooves formed in the vertical edge of the window sash and held in position by means of fastening members secured through the free ends of said respective tongues, and a second guide member formed with an elongated cylindrical portion adapted to fit within said slotted guide member and to frictionally engage the same for sliding adjustment of said window, and means for securing said second guide member to the window frame adjacent the path of travel of said sash.

5. An apparatus of the character described comprising a cylindrical guide member having a portion at one side adapted to be connected with a window frame, and a tubular guide member slotted at one side adapted to fit over said cylindrical guide member, said tubular guide member having adjacent each end a pair of rearwardly projecting resilient tongues and means for securing said tongues to the window sash at points adjacent the free ends of said tongues, whereby free adjustment of said slotted tubular member may be had with relation to said cylindrical guide member.

6. A self-adjusting window suspension comprising a pair of telescopically engaged guide members having sliding frictional engagement to permit relative longitudinal movement, and interlocked against lateral disengagement and means for connecting one of said guide members to a window frame and the other of said guide members to a window sash and supporting means for one of said guide members permitting the same to be held in free radial adjustment with its companion guide member to prevent binding action of the supporting means for said window and to provide a uniform degree of frictional engagement between the window frame and window sash whereby said window may be raised or lowered to any desired position of adjustment and maintained at such point by means of the frictional engagement of said guide members.

7. A self-adjusting window suspension comprising a pair of telescopically engaged guide members having sliding frictional engagement to permit relative longitudinal movement, and interlocked against lateral disengagement and means for connecting one of said guide members to a window frame and the other of said guide members within a groove formed longitudinally of the vertical edge of

the window sash and of a size to permit said member to have a slight degree of lateral motion therein, means formed on one guide member resiliently attaching the same with said groove whereby said guide member may move inwardly or outwardly in the plane of the sash or may be rocked transversely to a diagonal position without disturbing the frictional engagement of said guide member with its companion guide member.

8. A self-adjusting window suspension comprising a grooved guide member adapted to be associated with the lateral edge of a window sash and restricted from longitudinal displacement therefrom, a second guide member adapted to be engaged within said first-named guide member and longitudinally slideable relative thereto and interlocked against lateral disengagement and means for varying the frictional engagement of said last-named guide member with said first-named guide member.

9. A window construction having in combination a pair of guide members slidably associated for relative longitudinal sliding movement and interlocked against lateral disengagement, supports for said guide members, one of said guide members having transverse movement relative to its support, and means for restricting said last-named guide member from longitudinal displacement and at the same time substantially preventing the entrance of air.

10. Guide members for windows comprising a pair of elongated members adapted to be slidably engaged with each other for relative longitudinal sliding movement, and interlocked against lateral disengagement, means for connecting said members to supports, the connecting means of one of said guide members restricting the same from longitudinal displacement while permitting free transverse movement and at the same time substantially preventing the entrance of air.

Signed by me this 2nd day of April, 1927. 110
